DESIGN.

—o—
W. HALEY.

BASKET.

Ye. 18,566.

Patented Aug. 28, 1888.

UNITED STATES PATENT OFFICE.

WILLIAM HALEY, OF BEAVER FALLS, PENNSYLVANIA.

DESIGN FOR A BASKET.

SPECIFICATION forming part of Design No. 18,566, dated August 28, 1888.

Application filed August 3, 1888. Serial No. 281,914. Term of patent 14 years.

To all whom it may concern:

Be it known that I, WILLIAM HALEY, a citizen of the United States, residing at Beaver Falls, in the county of Beaver and State of Pennsylvania, have invented and produced a new and original Design for a Basket; and I do declare the following to be a full, clear, and exact description of the same, reference being had to the accompanying illustrations, forming a part thereof.

The drawing represents a perspective view of a glass basket embodying my design.

The leading feature of my design consists in the shape and ornamentation of the basket, which shows two similarly designed and rounded halves having a narrowed or contracted portion at the center, from which springs the handle. From the base of the basket projects a flaring base-rim, the design of which conforms to the general shape of the main body.

In the drawing, *a* represents the base or bottom of the basket. It is provided with a series of checkered or intersecting lines raised thereon with beveled edges.

b is the body of the basket, and *c c* are the two rounded halves constituting the body. These halves *c c* are contracted at their junction at the center of the basket, (shown at *d*.) The handle *e* springs from side to side.

f is the base-rim, which flares outwardly, and *g* are short legs or rests formed thereon. It may, however, be provided with a plain base.

h are a series of scallops formed on handle *e*, and *i* are ornaments, as shown, embedded in a roughened or frosted design, *k*, on the sides of the handle.

l represents vertical rib-work formed at the

base of the handle, where the glass is thickened to join the contracted sides of the basket. 40 The rounded halves *c c* may be polygonal in shape, if desired.

m is a beaded or rounded work or design, which may extend entirely around the edge of the article.

n are a series of ornamental rosettes formed on the outer sides of the basket, consisting of a radial series of ribs, *p*, and a circular rim of bead-work, *o*, arranged at the outer extremities of the ribs *p*.

q are a series of vertically-arranged ribs disposed around the sides or edges of the basket, and *r* are a series of beaded work around the base.

s are short legs depending from the base-rim.

t are a series of scallops upon the bottom of the rim.

s are a series of intersecting raised lines on the base-rim.

My design may be produced in any suitable material.

What I claim is—

The design for a basket herein shown and described, consisting of oppositely-enlarged ends, a contracted central portion, and a handle springing from opposite sides of the central portion, substantially as set forth, the whole having the shape and ornamentation shown.

In testimony whereof I affix my signature in presence of two witnesses.

WILLIAM HALEY.

Witnesses:

J. F. MERRIMAN,
WM. C. GALTON.
